UNITED STATES PATENT OFFICE.

RUDOLF HAGEN, OF COLOGNE, GERMANY.

MOTOR-VEHICLE.

SPECIFICATION forming part of Letters Patent No. 664,853, dated January 1, 1901.

Application filed December 23, 1897. Serial No. 663,170. (No model.)

To all whom it may concern:

Be it known that I, RUDOLF HAGEN, a subject of the King of Prussia, German Emperor, and a resident of Cologne-on-the-Rhine, in the Province of the Rhine, German Empire, have invented new and useful Improvements in Motor-Vehicles, of which the following is a specification.

My invention relates to improvements in motor-vehicles, and comprises specially the means for changing the speed of the vehicle without changing the speed of the motor. I attain this object by means of the lever mechanism illustrated in the accompanying drawings, in which—

Figure 1 is a view of the whole mechanism. Fig. 2 is a section of a detail of it on line X Y, Fig. 1.

The drawings represent the system of levers employed for changing the speed of the vehicle in connection with a single-cylinder engine. The fly-wheel *a* is not arranged on the main shaft *k*, but a special shaft *l* is provided which runs with greater velocity than the main shaft in order to be able to make the fly-wheel as small and as easy as possible and to effect an easier possibility of starting the engine by turning the fly-wheel. The movement of the main shaft *k* is transferred by means of a crank or an eccentric and of the connecting-rod *m* to the vertically-oscillating slotted arm *c*. In the slot of this slotted arm *c* slides a block *g*, that is pivotally connected with the slide-block *n*, Fig. 2. The latter slides in the slotted arm of a double-armed lever *e*, the ends of which are linked to the rods *h i*, so that the lever *e*, pivoted at *f*, oscillates together with the arm *c* and that the rods *h i* alternately move the driving-levers *o p*. The latter are loosely arranged on the axle of the vehicle and act in common with the clutch mechanism in the well-known manner only in one direction. It is clear that by means of the described parts a continued turning of the hind wheels (the driving-wheels of the motor-vehicle) takes place. The two connected slide-blocks *g* and *n* are by means of the connecting-rods *r* fixed to the common pivot-bolt of the two blocks fixed to the arm *s*, pivoted at *t*. This arm *s* is furnished with a handle and may be held in dif-

ferent positions by means of the ratchet *u* and the pawl *v*.

By dislocating the slide-block *g* within the slotted arm *c* the effective length of the latter is diminished or increased. As the slide-block *g* is connected with the slide-block *n* the latter is removed, together with block *g*, and the effective length of the upper arm of the lever *e* is correspondingly changed. The displacement of the slide-blocks is effected by means of the hand-lever *s* above mentioned. If the blocks are pushed up, the effective length of the lever *c* is diminished, while that of the lever *e* is increased, whereby a double diminution of the stroke of the driving-lever and a decrease of the velocity of the vehicle are attained. By pushing the slide-blocks down the speed of the vehicle is increased.

The stroke of the lever *e* may be increased to the maximum or diminished to zero—*i. e.*, to the complete stoppage of the vehicle although the motor continues its rotation. For the latter purpose the slot of the lever *c* is extended beyond the pivot *w*, so as to permit it to bring the slide-block in a position in which its pivot is coincident with the pivot *w* of the lever *c*. In this position of the slide-block *n* the oscillation of the lever *c* is no more transmitted to the lever *e*. The advantages of this lever mechanism are most important for motor-vehicles, as the mechanism for changing the speed of the vehicle exclusively consists of levers pivotally attached to inflexible axles mounted on the engine, and therefore the loss of power on account of friction is reduced to a minimum, and as by the employment of a double-armed lever, the movement of both arms of which is transferred to the axle by stiff rods, so that always one end of the lever is in action, only one system of levers is necessary.

What I claim, and wish to secure by Letters Patent of the United States, is—

1. In motor-vehicles the combination of an oscillating slotted one-armed lever *c* inflexibly pivoted to the engine at *w* and operated from the main shaft of the motor, with a double-armed lever *e* inflexibly pivoted to the engine at *f*, the upper arm of this lever being provided with a slot, stiff connecting-

rods attached to the ends of both arms of the double-armed lever *e* and adapted to transmit the motion of the lever to the driving-axle of the vehicle by means of a clutch mechanism, two slide-blocks *g* and *n* connected one with the other by means of a common pivot-bolt and fit for sliding in the slots of the levers *c* and *e* respectively and means for moving these connected slide-blocks *g* and *n* as and for the purpose set forth.

2. In motor-vehicles the combination of an oscillating slotted one-armed lever *c* inflexibly pivoted to the engine at *w* and operated from the main shaft of the motor with a double-armed lever *e* inflexibly pivoted to the engine at *f*, the upper arm of this lever being provided with a slot, connecting-rods attached to the ends of both arms of the

double-armed lever *e* and adapted to transmit the motion of the lever to the driving-²⁰ axle of the vehicle by means of a clutch mechanism, two slide-blocks *g* and *n* connected one with the other by means of a common pivot-bolt and fit for sliding in the slots of the levers *c* and *e* respectively, means for moving these connected slide-blocks *g* and *n* and a fly-wheel fixed to a special shaft, connected with a main shaft by means of gears as and for the purpose set forth.

In witness whereof I have hereunto set my ³⁰ hand in presence of two witnesses.

RUDOLF HAGEN.
